ROTARY ENGINE AND PUMP

Joseph Williams and Joseph Robert Troughear,
Auckland, New Zealand, assignors to Maximum
Pumps and Engines Limited, Auckland, New
Zealand

Application September 27, 1932, Serial No. 635,094
In New Zealand October 17, 1931

3 Claims. (Cl. 103—121)

- This invention relates to rotary engines and pumps, and provides an improved form thereof, adaptable for use either as a driven pump, or as a motor for generating power.
- 5 The improved form of engine or pump is characterized by the mounting of a rotor eccentrically within the cylindrical bore of a rotary casing and in contact therewith, the rotor and the casing being rotatable together in the same direction.
- 10 Constructionally, the improved engine or pump comprises a rotary casing containing a cylindrical bore and with end plates or covers attached, supported by aligned bearings, a rotor mounted eccentrically in said bore and in contact with
- 15 the casing, and a plate extending the full length of the bore attached to the casing between the inlet and outlet ports therein, and slidably in the rotor.

The invention will, however, be more fully described with the aid of the accompanying drawings, wherein

Fig. 1 is a longitudinal sectional elevation, of a pump constructed according to the invention,

Fig. 2 a cross sectional elevation taken through 25 A—A, Fig. 1,

Fig. 3 an elevation of the end plate or cover at the driving end of the pump,

Fig. 4 a cross sectional elevation on the line B—B, Fig. 3,

Fig. 5 a plan view of the rotary casing,

Fig. 6 a part sectional view on the line C—C,

Fig. 5,

Fig. 7 a part sectional view on the line D—D,

Fig. 5,

35 Figs. 8, 9 and 10 diagrammatic views illustrating the action of the pump,

Fig. 11 a longitudinal sectional view of a rotary internal combustion engine constructed according to the invention,

40 Fig. 12 a cross sectional view on the line E—E,

Fig. 11, and

Fig. 13 a cross sectional view on the line F—F,

Fig. 11.

The improved construction when used as a

45 pump adapted to be driven by any suitable motive power, comprises a rotary casing 1 containing a cylindrical bore 2 and fitted with end plates or

covers 3 and 4, (Figs. 1, 2, 3 and 4). The end

plate or cover 3 is the driving plate or cover, and

50 is formed with a boss 3^a adapted to be keyed on the end of a hollow shaft 5 (Fig. 1) mounted in pedestal bearings 6 on a base 7, said shaft 5 also having fast and loose pulleys 8, 8^a respectively, thereon.

55 The driving end plate or cover 3 is further se-

cured to the hollow shaft 5 by a set screw 9 in the boss 3^a, and also contains a chamber 10 open to the interior of the hollow shaft 5, and also in communication with the interior of the casing 1 through a horizontal port 11 and radial ports 12 in the wall of the latter, (Figs. 2, 5 and 7).

The end plate or cover 4 at the opposite end of the casing 1, contains a circular opening 13 around which is a ring 14, the latter entering a ring 15 fitted to or forming part of a pedestal bearing 16, and thereby rotatably supporting the casing 1 at its end distant from the hollow shaft 5, packing 16^b being provided between said rings 14, 15 to prevent leakage.

The rotor 17 (Figs. 1 and 2), is cylindrical and is mounted eccentrically within the cylindrical bore 2 of the rotary casing 1 by being supported on a stationary shaft 18 out of alignment with the hollow shaft 5, said shaft 18 being mounted at one end in the pedestal bearing 16 and passing through the opening 13 in the end plate or cover 4, and being supported at its other end by having an offset portion 18^a entered in a bearing 19 fitted in the end plate or cover 3 in alignment with the shaft 5, said end plate or cover 3 turning about said offset portion 18^a.

The pedestal bearing 16 contains a chamber 16^a provided with an outlet 20, said chamber 16^a also being connected through the circular opening 13 in the end plate or cover 4 with a space 21 in the rotary casing 1 between said plate or cover 4 on the one side and the closed end of the rotor 17 and a flanged ring 22 on the other side, said ring 22 being slidable on studs 23 in the end plate or cover 4 and being kept forced away from same by springs 24 around said studs and in compression between said plate 4 and ring 22.

The action of the springs 24 on the ring 22, presses the latter against the rotor 17, which is thereby forced along the shaft 18 towards the end plate or cover 3, between which and the rotor 17, a plain friction ring 25 is placed.

The space 21 in the rotary casing 1 is connected by a port 26 in the casing wall with a longitudinal port 27 also in said wall and from which ports 28 open into the interior of the casing (Figs. 2, 5 and 6).

The ports 28 on the one hand, and the ports 12 on the other hand, are separated by a plate 29 (Figs. 2 and 5) which extends along the full length of the rotor and has an enlarged rounded edge 29^a inserted in a correspondingly shaped groove 30 cut along the inner surface of the casing 1, so that said plate 29 is attached to the

100

105

110

latter, and extends into a radial slot 31 formed in the rotor 17.

The periphery of the rotor 17 is further grooved or recessed lengthways to take a series of spaced 5 parallel metal strips 32 (Figs. 1 and 2) the outer edges of which are shaped to fit against the inner surface of the casing 1, said strips 32 being retained on the rotor 17 by split rings 33 sprung into recesses in their ends, while springs 34 in 10 compression behind said strips 32 tend to force them outwards and into contact with the internal surface of the casing 1, when required.

The rotor 17 is counterweighted at 35 directly opposite the plate 29, to obtain the desired balance. Lubrication of the rotor 17 on its shaft 18 15 is provided for by passages 36 in the latter, supplied with lubricant through the pedestal bearing 16.

With the shaft 5 being driven through the fast 20 pulley 8 from any suitable prime mover, the casing 1 and rotor 17 are rotated together, the connecting means between said casing and rotor being the plate 29, the casing 1 in effect rolling around on the rotor 17, between which and the 25 plate 29, sliding movement takes place at the connected portions of the rotor and casing, due to difference in location of the centres thereof. If, therefore, the hollow shaft 5 be connected with fluid to be pumped, and the casing 1 and 30 rotor 17, rotated in the direction indicated by the arrows, the action will be as follows:—

It will be noted that the ports 12 (inlet ports) and the ports 28 (outlet ports), are at all times separated by the plate 29, and that the rotor 17 35 is always in contact with the interior of the casing 1 along a horizontal line at the highest point "h" (Figs. 8, 9, 10) of the latter, but upon the casing 1 and rotor 17 being rotated in the direction indicated, it will be found that as the plate 40 29 travels away from said highest point "h", a space "a" bounded by said plate 29, the rotor 17 and the casing 1 (Fig. 8), commences to open up, and said space "a" by its expansion is responsible for fluid being drawn in through the ports 12, 45 port 11, chamber 10 and shaft 5, to behind the plate 29, as indicated in Figs. 8 and 9.

This drawing of fluid into the space "a" between the rotor 17 and the casing 1 behind the plate 29 continues until such time as the 50 inlet ports 12 again pass the point "h" when the drawn in fluid becomes separated from the inlet ports 12, by said point "h" (Fig. 10), the rotor 17, casing 1, and plate 29 by the continued rotation of the rotor and the casing, then proceeding 55 to draw in a fresh supply of fluid through the ports 12, which fluid is however kept apart or is separated from the previously drawn in fluid, by the point "h". The plate 29 is now behind the 60 previously drawn in fluid (Fig. 10), said fluid owing to its being contained in a space which decreases as the plate 29 moves towards the point "h", is expelled by said plate through the ports 28, and ultimately discharged from the pump via the ports 27 and 26, space 21, openings 65 13, pedestal bearing 16 and pipe 20.

Continued rotation of the casing 1 and rotor 17 is responsible for a continuous drawing in of fluid through the ports 12 to behind the plate 29, which fluid cannot however pass the point 70 of contact between the casing 1 and rotor 17, so that ultimately it is cut off from the suction side of the plate 29, and becomes subjected to the pressure side of the latter, to be finally expelled through the ports 28, while a further charge of

fluid is being dealt with by the suction side of said plate 29.

The construction when used as an external combustion motor, operates in a similar manner to the pump, but is duplicated to provide for compression of the charge to be fired, before passing the latter to a combustion chamber from which after ignition of the charge the resultant gases are permitted to expand between a rotor and the casing, in order to impart rotary motion to same.

Upon referring to Figs. 11, 12 and 13 of the drawings, it will be seen that the rotary casing 1 is divided by a partition 36^a into two side by side chambers 39, 40, each of which contains a rotor 17 constructed and operated and connected with the casing 1 by plates 29, the same as before described, except that they are mounted to rotate on a cranked portion 37^a of a stationary shaft 37 fixed in pedestals 38, and on the aligned portions of which shaft the casing 1 is rotatably mounted.

Chamber 39 functions as the fuel compressor, a charge of fuel mixture being drawn from a carburettor (not shown) through an intake 41 into a circular recess 42 in a non-rotary casting 43 on one end of the shaft 37, said casting 43 being pressed by springs 44 acting against the adjacent pedestal 38, so that the recess 42 registers with a similar recess 45^a in a boss 45 on the end or cover plate 46, a port 47 in which connects the recess 45^a with a port 48 in the casing wall, a further port 49 in the latter connecting the port 48 with the interior of the chamber 39 at one side of the plate 29.

The charge drawn into the compressor chamber 39 is compressed and finally passed to the ports 50, 51, 52, (Fig. 12), and after forcing open the spring loaded check valve 53 enters the combustion chamber 54 on the outside of the casing 1, where at the appropriate moment it is fired by means of a spark plug 55.

From the combustion chamber 54, the ignited charge is admitted by a cam operated and spring loaded valve 56 to a port 57 which passes the 120 gases into the chamber 40 behind the plate 29 so that said gases expanding in the chamber 40 between the rotor 17 and the casing 1, impart turning motion to the whole construction in the direction indicated by the arrows, the expanded 125 gases being later separated by the point of contact of the rotor 17 with the casing 1 from the following incoming gases and expelled through the ports 58, 59 and 60 and circular recesses 61, 62, to the exhaust port 63.

The circular recesses 61, 62 are arranged to co-act in a similar manner to the circular recesses 42, 45^a, the casting containing the recess 62 being water jacketed and held against rotary movement on an extension 64^a of the end or cover plate 64 which is adapted to drive a shaft 65 through toothed gearing 66.

Also the rocker arm 67 for opening the valve 56 against the action of its spring, and which is mounted on the end or cover plate 64 and travels with the latter, is actuated to operate said valve 56 at the appropriate moment by its end carrying the friction roller 68 travelling around a cam 69 on the non-rotary casting containing the circular recess 62.

What we do claim and desire to obtain by Letters Patent of the United States of America is:—

1. A rotary pump comprising a rotary casing including a cylindrical body having inlet and outlet ports therein, exterior chambers on the body re-

80

spectively enclosing said inlet and outlet ports, end covering plates attached to the respective ends of the body and respectively provided with ports leading to the inlet chamber and from the 5 outlet chamber, aligned bearings supporting said end plates, a rotor mounted eccentrically in the body and in contact with the inner surface thereof, a plate extending the full length of said chambers and attached thereto between the inlet and 10 outlet ports and slidably radially in said rotor, a plurality of pedestals, a hollow shaft in one of said pedestals and acting to support the bearing of one end plate, the other bearing being in the form of a ring supported by another of the pedestals, 15 said latter pedestal being hollow and constituting a discharge outlet, and the ring serving to establish communication between the port in the adjacent end plate and the hollow pedestal.

2. A rotary pump as claimed in claim 1, wherein 20 the end plate supported by the hollow shaft is provided on its inner surface with a central bearing, and wherein a shaft is provided for loosely supporting the rotor and includes an offset end por-

tion journaled in the said central bearing while the other end passes through the ring bearing and is journaled in the upper end of the hollow pedestal so as to support the rotor eccentrically of the casing.

3. A rotary pump as claimed in claim 1, wherein 25 in the end plate supported by the hollow shaft is provided with a central bearing on its inner surface, and wherein a shaft is provided for the rotor for loosely supporting the rotor and includes an offset end portion journaled in the said central bearing, the other end of said shaft passing through the ring bearing and being journaled in the upper end of the hollow pedestal so as to support the rotor eccentrically of the casing, a ring adjacent the end plate having a discharge port, means slidably and yieldably mounted on 30 said ring in spaced relation to the said end plate and in contact with one end of the rotor, said ring cooperating with the end plate and forming part of the discharge outlet.
